UNITED STATES PATENT OFFICE

2,644,632

BOX

Clarence Lloyd Claff, Randolph, Mass., assignor
to Norfolk Paper Company, Inc., Randolph,
Mass., a corporation of Massachusetts

Application May 1, 1947, Serial No. 745,208

1 Claim. (Cl. 229—34)

1

The present invention relates to cardboard boxes and more particularly to boxes carrying a removable stock control tag and to the box blank therefor.

It is the object of the present invention to provide a box of the above type which is made or "set up" from a flat blank which during the blank-forming operations is subjected to certain additional operations to provide for the stock control tag.

With this object in view the present invention consists in the blank and the box made therefrom herein shown and described and more particularly defined in the appended claim.

In the accompanying drawings showing blanks and boxes embodying the present invention, Fig. 1 is a perspective view of a flat blank as it comes to the operator of the setting-up machine; Fig. 2 is a corresponding view of one end of the blank after it has been partially set-up or folded into box form; Fig. 3 shows in similar view the same box end after completion of the box ready to receive a stock control tag, and Fig. 4 shows such a tag separately; Fig. 5 is a vertical section on an enlarged scale on lines 5—5 of Fig. 3; Fig. 6 is a similar view on lines 6—6 of Fig. 8 with the stock tag in position in the box end; Fig. 7 is a horizontal view on lines 7—7 of Fig. 8; and Fig. 8 is an elevation of the end of the box with the stock tag in place.

In the form of the present invention shown in Figs. 1 to 8 of the drawings, the box blank is so cut at one end and its end parts so adhesively secured together that a pocket is formed in such end adapted to receive a stock tag which may be inserted through an opening in the upper edge of the box end. The tag is so positioned in the pocket that the notations or printing on the tag are opposite an opening or window in the box end and in full view of the clerk. When desired, the tag may be raised and removed from the pocket, and thereafter be used in the customary manner to record a sale of the contents of the box and to provide a check on the goods still in stock.

As shown in Fig. 1, the improved blank comprises the usual body or bottom portion 12 with integral side wings 14 having corner lap extensions 16 and with end wings 18 having extensions 20. Fold or crease lines 22 separate the side wings 14 from the bottom 12, and other fold lines 24 separate the extensions 16 from the side wings 14. Fold lines 26 separate the end wings 18 from the bottom 12, while lines 28 separate the extensions 20 from the end wings 18.

2

The corner lap extensions 16 of the side wings 14 are separated from the end wings by the wedge-shaped notches 30, and said extensions are shortened as at 32, to avoid the over-lapping of the extensions when they are folded inwardly as shown in Fig. 2.

The box is set-up in the usual manner by turning the side wings 14 upwardly and the corner lap extensions 16 inwardly, as shown in Fig. 2. The end wing 18 is then turned upwardly and its extensions 20 folded inwardly over the corner laps in the usual manner, as indicated in Fig. 3. The side wing extensions 16 and the end wings 18 and extensions 20 are secured together by adhesive applied to the end wings and their extensions.

The blank as above described is a common type of blank used extensively for certain lines of boxes, such, for example, as shoe cartons, and in order to adapt it for use with a stock control tag it is subjected in the blank forming process to additional cutting or punching operations. Also, in the setting-up operations the adhesive is applied to only the shaded portion 34 of the end wing at one end of the box and of its extension for a purpose hereinafter set forth. In these additional cutting operations the opening 36 in the end wing 18 is formed, and also the transverse slot 38 lying across the fold line 28 and partly in the end wing 18, and partly in the extension 20.

The slot 38, it will be noted, is aligned longitudinally of the blank with the adjacent opening 36, and the slot at each end projects beyond the side walls of the opening.

When the end of the box with the opening 36 and slot 38 and the adhesively coated area 34 is folded into box formation, as shown in Fig. 3, a recess or pocket is formed in the end of the box adapted to receive a stock control tag, such as shown in Fig. 4, with the notations or printing positioned opposite the opening or window 36, the tag being inserted and removed through the slot 38 which lies in the top edge of the box end.

The back member or wall of this tag-receiving pocket is formed by the inturned side wing extensions 16, the inner faces of which are adhesively secured adjacent their top edges to the inturned overlying end wing extension 20, while their outer faces spaced from the opening 26, are adhesively secured to the inner face of the end wing 18. See Figs. 2 and 5. The front wall of the pocket is formed by the middle portion of the end wing 18, which is free from adhesive. Thus, when the tag 39 is inserted through the

slot 38 and into the pocket as shown in Figs. 6, 7 and 8, its top, bottom, and side marginal portions are securely held between the front and back walls of the box end.

It will be observed that the tag receiving pocket is formed in the end of the box when the blank is set up in the customary manner, without requiring additional or different folding or pressing mechanism from that used with the conventional or standard form of blank and box. The manipulations of the operator in setting-up the box are exactly the same as with the standard blank and box, the only change in such setting-up operation being that the adhesive is applied to only a portion of one of the end wings and not to its entire surface.

The stock control tag may be cut from any suitable paper or light cardboard, of a size to fit easily within the pocket, and printed with suitable notations such as the stock number, the size and price, as shown in the drawings. Before the tags are inserted in the boxes the identifying stock numbers, sizes and prices will be written or stamped upon them, corresponding to the shoes or other goods packed or to be packed in the boxes.

In the use of the present invention in the form shown in Figs. 1-8, a blank is formed as shown in Fig. 1 by cutting and scoring the pasteboard or other material, and thereafter applying adhesive to the shaded areas. The blank is then folded into box form, as shown in Figs. 3 and 5, and a printed stock control tag, as shown in Fig. 4, is inserted as indicated in Figs. 6, 7 and 8.

When a sale is made of the goods contained in the box, the tag is removed and used first as a sales ticket, and then as a stock control ticket. If desired, the box may be used again with another stock control tag appropriately marked and inserted in position in the box.

While the present invention is shown and described in a particular construction and arrangement, it is to be understood that it is not necessarily limited thereto, but may be embodied in other forms and arrangements within the scope of the language of the appended claim.

Having thus described the invention, what is claimed is:

A box of cardboard or the like comprising a

bottom portion with side wings and end wings integral therewith, the end wings having end extensions thereon, the side wings having corner lap extensions turned inwardly in their entirety across the box ends with their free ends adjacent one another to form substantially continuous inner end walls at the ends of the box, and the end wings being turned upwardly to form the outer end walls of the box with said end extensions being folded over the top edges of the inner walls and downwardly against the inner faces thereof, the end wings and end extensions being adhesively secured to the inner end walls, one end wing having an opening therethrough intermediate the top edge and the bottom of said box end, said one end wing and its folded over end extension being cut away in the line of the fold to form a transverse slot extending below the top edge of the inner wall of the box end and terminating above said opening, the contacting faces of the inner and outer end walls adjacent said opening and between said opening and said transverse slot being free from adhesive and unattached to one another to form a pocket to receive a removable tag passed through the transverse slot and into register with said opening in the outer end wall.

C. LLOYD CLAFF.
